LOCK FOR COUNTERBALANCED ELEVATOR DOORS

Robert S. Peelle, Hollis, N. Y., assignor to The Peelle Company, Brooklyn, N. Y., a corporation of New York

Application June 23, 1933, Serial No. 677,304

7 Claims. (Cl. 187—31)

The invention relates to locks for counterbalanced elevator doors, and more particularly to a combined mechanical lock and electric interlock.

5 Counterbalanced elevator doors of the type to which the present invention relates are used in connection with freight elevators in warehouses, loft and similar types of buildings.

In some instances the freight elevators are 10 operated by a regular attendant, while in other instances, these elevators are operated by porters, stevedores or other handlers of freight being carried on the elevator. To afford safeguards against the extension of fires in such 15 buildings, the doors are required to be fire retardant, and in many jurisdictions there are ordinances requiring the use with such doors of an electric interlock by means of which the application of power to an elevator car is prevented unless all of the doors in a shaft are 20 fully closed and locked.

In some localities it is required that the electric interlock be positively actuated to interrupt the circuit to the motor imparting movement to 25 the car before the door can be opened, thus preventing tampering with the interlock mechanism in a manner to make it inoperative. This is referred to merely because the lock of the invention is shown as being of this particular 30 type.

It has long been the practice to equip counterbalanced freight elevator doors with a locking mechanism consisting of laterally movable bolts carried by the lower door section and engageable 35 with keepers upon the guide rail structure at opposite sides of the door opening, and having a central rotatable plate pivotally connected with said bolts for ensuring simultaneous movement thereof into or out of engagement with 40 said keepers. It has also been a common practice to provide an electric interlock mechanism actuated by one of said bolts. With such mechanisms, both bolts were always under the control of the central actuating mechanism above referred to, and this mechanism was automatically 45 actuated as a result of the movement of the bolts by a striker plate associated with one or both of said keepers.

With a locking mechanism carried by the 50 lower door section, this section, when the door was closed, was held in its uppermost position so as to relieve the chains from the load of the lower door section when the door was closed.

With the above conditions in mind, I have 55 provided a lock for counterbalanced elevator doors, which may be applied to the upper section of a counterbalanced freight elevator door so as to permit the opening of the door by the application of upward stresses to the lock actuating mechanism, said lock being adapted to

control the functioning of an electric lock mechanism as to one bolt carried thereby, and as to the other bolt thereof, to bind the two door sections together in a manner to hold them in the closed and locked position. 5

The bolts have a right line movement into and out of engagement with the interlock mechanism and the keeper member co-operating therewith respectively, and while the actuating mechanism simultaneously actuates both bolts when 10 opening a door, when closing a door the bolts have movement entirely independently of the actuating mechanism and each other. This condition is desirable inasmuch as the construction of the ordinary electric interlock is such as to 15 require a time interval for the actuation of the bolt co-operating therewith considerably greater than is required for the actuation of a bolt for the purpose of ensuring its engagement with the co-operating keeper carried by one of the door 20 sections.

By using oppositely movable bolts having right line movement, the slotting of the angle metal frame of the lower door section to form a keeper 25 adapted to co-operate with a hooked latch member is unnecessary, and it is possible to locate the actuating mechanism either centrally of the door or at any point between the sides thereof since this position of the actuating mechanism merely necessitates the use at opposite sides of 30 the door of bolts of proper relative lengths, the construction of the lock of the invention being such as to not only permit longitudinal adjustment of the bolts to ensure a proper setting thereof in relation to the interlock mechanism 35 when installing the doors in an elevator shaft, but to permit the determination of the length of the bolts according to the position of the actuating mechanism therefor by a selection of bolt parts of the required lengths. 40

The use of bolts having a right line movement, and the movability of these bolts in relation to their actuating mechanism upon the closing of the door, not only permits a fairly close adjustment of the bolts in relation to the 45 electric interlock and the keeper with which they respectively co-operate, but also permits the use of an actuating mechanism operative upon the bolts at a leverage sufficiently great to assure ease in the release of the locking mechanism. 50

The lock of the invention is composed of few parts, which may be made of materials and of a design possessing great strength notwithstanding that they must be confined within a narrow 55 space.

The invention consists primarily in a lock for counterbalanced elevator doors embodying therein a housing carried by one of the sections of said door, bolts slidably mounted in and ex- 60

tending beyond opposite sides of said housing and of the door, a spring having a normal tendency to impart a right line movement to said bolts outwardly of the housing, actuating means 5 for said bolts comprising a pivotal member, substantially diametrically opposite studs carried thereby, each of said bolts having a shoulder adapted to be engaged by a stud upon said pivotal member and an operating handle for said 10 member, an electric interlock mounted adjacent the door and having a striker and keeper plate engageable by one of said bolts, and a striker and keeper member carried by the other door section with which the other bolt co-operates; 15 and in such other novel features of construction and combination of parts, as are hereinafter set forth and described and more particularly pointed out in the claims hereto appended.

Referring to the drawing, 20 Fig. 1 is a view from the shaft side, of a standard form of counterbalanced elevator door having the lock of the invention applied thereto;

Fig. 2 is a laterally condensed view of the lock mechanism upon a larger scale with the face 25 plate of the lock housing removed and parts of the walls broken away; and

Fig. 3 is an exploded view of the central portion of the lock mechanism including the actuating mechanism.

Like numerals refer to like parts throughout the several views.

The characteristics of the lock of the invention are such as to adapt it only to use with counterbalanced freight elevator doors. This 35 type of door has two sections which are oppositely and vertically movable in the same, or in parallel planes, and are used to close door openings which vary greatly in width, said door openings seldom being less than six feet in 40 width, and sometimes being of a width of fifteen or twenty feet. Such doors can be operated only from the shaft side of the door opening by the attendant upon an elevator car.

In the accompanying drawing, I have shown a 45 standard form of such a door which consists of an upper door section 10, a lower door section 11, and flexible connections 12 between the door sections passing over sheaves 13 which are usually located adjacent the lintel of a door opening.

In counterbalanced elevator doors each section is formed of a rectangular angle metal frame 14, the opening within which is closed by a panel which in some instances consists of corrugated sheet metal, and in other instances consists of a wood core having a metal sheathing. Each door section is movable upon a guide rail structure extending throughout the shaft at opposite sides of the various door openings therein, such structures being shown in the drawing at 55 15 and 16. The housings of the sheaves 13 are carried by the guide rail structures 15 and 16 respectively.

Also carried by one of the guide structures is 60 an electric interlock mechanism 17 controlling the application of power to the elevator car. The details of this mechanism are immaterial to the present invention, it being merely necessary to understand that it has a striker and keeper plate 18.

The lower door section 11 is provided with what is known as a hanger bar 19 which forms a part of the top rail structure of this section, and has projecting ends to which the flexible 75 connections 12 are attached. This hanger bar

is made of angle metal, except as to the projecting ends thereof which have the horizontal flange of the angle bar 19 cut away so as to permit said ends to extend across the edge of the adjacent guide rail structure.

All of the structural characteristics above referred to are old and well known in the counterbalanced freight elevator door art, and are referred to merely to enable a better understanding of the reasons for, and the mode of operation 10 of, the lock mechanism of the invention.

The lock of the mechanism comprises a housing 20 having, adjacent the bottom thereof, lateral extensions 21 and 22. This housing is secured to the panel of the upper door section 11 adjacent the lower edge thereof by means of bolts 23 passing through the door and through the extensions 21 and 22 and lug 24 adjacent the top of the housing. The lower part of the housing is provided with a guide flange 25 extending 20 throughout the width of the housing and the length of the extensions 21 and 22. Said extensions are also provided with guide flanges 26 and 27 parallel with the flange 25.

Slidably mounted within the housing 20 are 25 oppositely movable bolts 28 and 29, said bolts being positioned between the flanges 25 and 26 and 27 respectively, and extending beyond opposite sides of the housing. Each bolt is provided with a cutout shown at 30 affording clearance adjacent the securing bolts 23 passing through the extensions 21 and 22, and utilizing the nuts upon these bolts to prevent any possibility of the escape of the bolts from the housing, and arrangement supplementing the action of the bolt 35 actuating mechanism, to be hereinafter described, in securing this permanency in the relation of the bolts and the housing.

To permit the use of a standard lock mechanism with doors of different dimensions, the 40 bolts 28 and 29 respectively are provided with slots 31 and 32 by means of which and adjusting bolts 33, bolt extensions 34 and 35 may be incorporated in the lock structure. By this construction, bolt extensions of any desired length 45 may be used, the slots 31-32 and the adjusting bolts 33 permitting a limited range of movement of the bolt extensions in securing a proper setting of same in relation to the keepers with which they co-operate.

As shown in the drawing, the bolt extension 55 34 is provided with a hooked end 36 to ensure the positive interruption of the circuit supplying power to the elevator with the release of the locking mechanism prior to the initial opening movement of a door. The two bolts 28 and 29 are in axial alignment one with the other, and have a right line movement away from each other when the bolts are shot, and toward each other when the lock is to be released.

Said bolts are acted upon by a coiled spring 60 37, the opposite ends of which bear against spring seats 38 and 39 formed in the adjacent ends of the bolts. This spring has a normal tendency to force the bolts outwardly of the 65 housing 20 to an extent limited by the bolt actuating mechanism and the securing bolts 23.

The housing 20 is provided with a bearing stud 40 upon which is mounted an actuating plate 41 having substantially diametrically opposite 70 studs 42 and 43 and a radially extending actuating handle 44 projecting laterally from the housing. The bolt 28 is provided with an offset shoulder 45 engaged with the stud 43 by the action of the spring 37. The bolt 29 is pro- 75

vided with an offset arm 46 having a shoulder 47 which is engaged with the stud 43 by the action of the spring 37. The offset arm 46 is used so as to position the shoulders 45 and 47 substantially diametrically opposite each other in relation to the axis of the actuating plate 41, so that the turning of this plate will simultaneously draw both bolts 28 and 29 inwardly of the housing against the tension of the spring 37. It will be noted that with this construction and arrangement of parts, the bolts 28 and 29 may receive movement inwardly of the housing as a result of the turning of the plate 41, but may also have such movement entirely independently of said plate and of the studs carried thereby.

The shoulders 45 and 47 are of a length to preclude any possibility of the studs passing out of engagement therewith as a result of the turning movement of the plate carrying said studs, although the arcuate movement of said studs is not sufficiently long to require any substantial length of said shoulders.

The bolt 28 is adapted to co-operate with the striker and keeper plate 18 of the electric interlock mechanism with the two-fold function of assisting in preventing opening movement of the door and the control of power to the elevator car operating motor. This bolt therefore serves to restrain upward movement of the door section 10, and through the flexible connections 12, downward movement of the lower door section 11. It is desirable, however, to relieve the electric interlock mechanism from excessive stresses resulting from possible attempts to open the door from the floor side, and also to prevent possible separation of the two door sections through slack in the chains. To do this, I provide upon the hanger bar of the lower door section, a striker and keeper hook 48 engageable by the bolt 29 when the two door sections are in the closed position, this construction not only serving to protect the electric interlock from the stresses above referred to, but firmly binding the two door sections together at one edge thereof. This bolt and keeper arrangement will prevent rebound of the doors following the closing movement, and is adequate because of the counterbalancing of the two door sections to prevent their separation after they have once been brought into the fully closed position.

The various parts of the lock mechanism, shown more particularly in Fig. 3, may be made of malleable iron castings requiring substantially no machine finishing thereof.

The ends of the bolt members 28 and 29 adjacent the stop 32 are reduced in thickness as compared with the remaining portions of these members, so as to facilitate the mounting of the bolt extensions 34 and 35 thereon, which sections 34 and 35 carry the adjusting bolts 33. The door section 10 has secured thereto straps 49 guiding the bolt extensions 34 and 35 adjacent the angle metal frame of the door.

While, in the accompanying drawing, the bolt actuating mechanism is shown as being mounted substantially centrally of the width of the door, the use of the bolt extensions permits this mechanism to be located adjacent the side edge of the door where it is conveniently accessible to the attendant. This construction has the further advantage that it permits the use of a standard construction of lock actuating mechanism upon doors of different widths.

While the operation of the lock of the invention is apparent from the foregoing description, it is desired to stress certain conditions which make the lock particularly adaptable to the type of door with which it is designed for use.

When opening counterbalanced freight elevator doors, the operator applies an upward stress to the operating handle 44 forcing it into the position shown in dotted lines Fig. 2. While passing to this position, no upward movement is imparted to the door section 10, but the plate 41 is so turned as to cause the pins 42 and 43 thereon to draw both bolts toward the center of the door, thus simultaneously permitting the actuation of the electric interlock to prevent the application of power to the elevator car, and disengaging one bolt from the striker plate of the electric interlock mechanism and the other bolt from the keeper 48. Consequently, the attendant, by a continuing upward pressure upon said handle, will consecutively unlock the door and impart an upward impetus to the upper door section 10.

The tension of the spring 37 is not sufficiently great to offer enough resistance to the turning movement of the plate 41 to cause the application of any lifting stresses to the door. This avoids the development of frictional resistance to the movement of the bolts in relation to their co-operating keepers. By using a plate 41 having studs 42 and 43 acting upon the bolts 28 and 29, and by using a long handle 44 carried by said plate 41, pressure applied to said handle acts upon the bolts at an effective leverage. This also ensures a desired length of movement of the bolts with small turning movement of the plate.

When closing a door, the attendant merely exerts a downward pull upon the upper door section 10. Since the two sections are approximately of the same weight, the closing movement of the door is fairly rapid and the acquired momentum is sufficiently great to permit a substantially complete closing movement of the doors following the application of an initial closing impulse thereto by the attendant.

As the upper door section approaches its fully closed position, the bolt extension 34 engages the striker plate 18 of the electric interlock housing before the bolt extension 35 is in the operative relation to the keeper hook 48. This condition is unavoidable because of structural characteristics inherent to the type of electric interlocks used in connection with counterbalanced elevator doors. As the end of said bolt 34 passes the inclined portion of said striker plate, the entire bolt passes inwardly of the housing 20 against the tension of the spring 37, no movement being imparted to the actuating plate 41 since the shoulder 45 merely passes from its engaging relation therewith.

As the bolt extension 35 engages the hooked keeper 48 carried by the hanger bar 19 of the lower door section, it will be forced toward the housing 20 against the tension of the spring 37, the shoulder 47 passing from its engagement with the stud 42, no movement being imparted to the plate 41.

As the bolt 34 comes into alignment with the opening in the striker plate 18, the end of the bolt 35 passes below the hooked end of the keeper 48 and both bolts are forced outwardly of the housing 20 by the spring 37. This movement is sufficiently rapid, because of the spring being

under its greatest tension at this time, to avoid possible rebound of the two door sections following their impact upon the completion of their closure movement.

5 The right line movement of the movable bolts ensures a desired ease of movement thereof that avoids binding action, particularly during the release of the locking mechanism.

By actuating the bolts by studs engageable 10 with, but unconnected thereto, movement of the bolts when closing a door imparts no movement to the handle 44 and the right line movement of the bolts above referred to is secured.

It is not my intention to limit the invention 15 to the precise details of construction shown in the accompanying drawing, it being apparent that such may be varied without departing from the spirit and scope of the invention.

Having described the invention, what I claim 20 as new and desire to have protected by Letters Patent, is:—

1. A lock for counterbalanced elevator doors embodying therein a housing carried by one of the sections of said door, bolts slidably mounted 25 in and extending beyond opposite sides of said housing and of the door, a spring having a normal tendency to impart a right line movement to said bolts outwardly of the housing, actuating means for said bolts comprising a pivotal member, substantially diametrically opposite studs carried thereby, each of said bolts having a shoulder adapted to be engaged by a stud upon said pivotal member and an operating handle 30 for said member, an electric interlock mounted adjacent the door and having a striker and keeper plate engageable by one of said bolts, and a striker and keeper member carried by the other door section with which the other bolt co-operates.

40 2. A lock for counterbalanced elevator doors embodying therein a housing carried by one of the sections of said door, and having parallel spaced guide flanges, axially alined bolts mounted between said guide flanges and extending beyond opposite sides of said housing and of the door, adjacent ends of said bolts having spring seats formed therein, a coiled spring having its opposite ends engaged with said spring seats, actuating means for said bolts comprising a pivotal member, substantially diametrically opposite studs carried thereby, each of said bolts having a shoulder adapted to be engaged by a stud upon said pivotal member and an operating handle for 45 said member, an electric interlock mounted adjacent the door and having a striker and keeper plate engageable by one of said bolts, and a striker and keeper member carried by the other door section with which the other bolt co-operates.

55 3. A lock for counterbalanced elevator doors embodying therein a housing carried by one of the sections of said door, axially alined bolts slidably mounted in, and extending beyond, opposite sides of said housing and of the door, one 60 of said bolts having an offset shoulder formed on the end thereof within the housing, and the other of said bolts having an offset arm provided with a shoulder positioned in substantial alinement with, but spaced in relation to, the shoulder upon said other bolt, a spring having a normal tendency to impart a right line movement to said bolts outwardly of the housing, actuating means for said bolts comprising a member pivoted intermediate said shoulders, diametrically opposite studs thereon engageable with said shoulders, and a radially extending operating handle for said member, an electric interlock mounted adjacent the door and having a striker and keeper plate engageable by one of said bolts,

ders respectively, and a radially extending operating handle for said member, an electric interlock mounted adjacent the door and having a striker and keeper plate engageable by one of said bolts, and a striker and keeper member carried by the other door section with which the other bolt co-operates.

4. A lock for counterbalanced elevator doors embodying therein a housing carried by one of the sections of said door, bolts slidably mounted 10 in, and extending beyond, opposite sides of said housing, bolt extensions adjustably secured to said bolts and projecting beyond the edges of said door, a spring having a normal tendency to impart a right line movement to said bolts outwardly of the housing, actuating means for said bolts comprising a pivotal member, substantially diametrically opposite studs carried thereby, each of said bolts having a shoulder adapted to be engaged by a stud upon said pivotal member and an operating handle for said member, an electric interlock mounted adjacent the door and having a striker and keeper plate engageable by one of said bolts, and a striker and keeper member carried by the other door section with which the other bolt co-operates.

5. A lock for counterbalanced elevator doors embodying therein a housing carried by one of the sections of said door, axially alined bolts slidably mounted in, and extending beyond, opposite sides of said housing, one of said bolts having an offset shoulder formed on the end thereof within the housing, and the other of said bolts having an offset arm provided with a shoulder positioned in substantial alinement with, but spaced in relation to, the shoulder upon said other bolt, bolt extensions adjustably secured to said bolts and projecting beyond the edges of said door, a spring having a normal tendency to impart a right line movement to said bolts outwardly of the housing, actuating means for said bolts comprising a member pivoted intermediate said shoulders, diametrically opposite studs thereon engageable with said shoulders respectively, and a radially extending operating handle for said member, an electric interlock mounted adjacent the door and having a striker and keeper plate engageable by one of said bolts, and a striker and keeper member carried by the other door section with which the other bolt co-operates.

6. A lock for counterbalanced elevator doors embodying therein a housing carried by one of the sections of said door, and having parallel spaced guide flanges, axially alined bolts mounted between said guide flanges and extending beyond opposite sides of said housing, adjacent ends of said bolts having spring seats formed therein, and one of said bolts having an offset shoulder formed on the end thereof within the housing, and the other of said bolts having an offset arm provided with a shoulder positioned in substantial alinement with, but spaced in relation to, the shoulder upon said other bolt, bolt extensions adjustably secured to said bolts and projecting beyond the edges of said door, a coiled spring having its opposite ends engaged with said spring seats, actuating means for said bolts comprising a member pivoted intermediate said shoulders, diametrically opposite studs thereon engageable with said shoulders respectively, and a radially extending operating handle for said member, an electric interlock mounted adjacent the door and having a striker and keeper plate engageable by one of said bolts,

and a striker and keeper member carried by the other door section with which the other bolt co-operates.

7. A lock for counterbalanced elevator doors embodying therein a housing carried by the upper section of said door, bolts slidably mounted in, and extending beyond, opposite sides of said housing and of the door, a spring having a normal tendency to impart a right line movement 10 to said bolts outwardly of the housing, actuating means for said bolts comprising a pivotal member, substantially diametrically opposite

studs carried thereby, each of said studs having a shoulder adapted to be engaged by a stud upon said pivotal member and an operating handle for said member, an electric interlock mounted adjacent the door and having a striker and keeper plate engaged by one of said bolts, a hanger bar upon and projecting beyond the edge of the lower door section, and a hooked striker and keeper member projecting upwardly from said hanger bar into engaging relation 10 with the other of said bolts.

ROBERT S. PEELLE.
